(Cl. D89—1)

To all whom it may concern:

Be it known that we, James Harvey Chandler and Allen J. Eggleston, both citizens of the United States, respectively residing at Oak Park and Chicago, in the county of Cook and State of Illinois, have invented a new, original, and ornamental Design for a Kitchen Tool or Similar Article, of which the following is a specification, reference being had to the accompanying drawing, forming part thereof.

Fig. 1 is a front elevational view of the kitchen tool or similar article showing my new design.

Fig. 2 is a side elevational view thereof; and Fig. 3 is a bottom plan view thereof.

We claim:

The ornamental design for a kitchen tool or similar article, as shown.

JAMES HARVEY CHANDLER.
ALLEN J. EGGLESTON.
